UNITED STATES PATENT OFFICE.

CHARLES W. FINLEY, OF BATTLE CREEK, MICHIGAN.

ELECTRICAL CONNECTOR.

1,296,061.

Specification of Letters Patent. Patented Mar. 4, 1919.

Application filed April 13, 1918. Serial No. 228,297.

To all whom it may concern:

Be it known that I, CHARLES W. FINLEY, a citizen of the United States, residing at Battle Creek, county of Calhoun, State of Michigan, have invented certain new and useful Improvements in Electrical Connectors, of which the following is a specification.

This invention relates to improvements in electrical connectors.

The main objects of this invention are:

First, to provide an improved electrical connector which may be quickly installed or applied and one which when applied is very secure and effective as a conductor.

Second, to provide an improved electrical connector which is compact, simple and economical in structure.

Further objects, and objects relating to structural details, will definitely appear from the detailed description to follow.

I accomplish the objects of this invention by the devices and means described in the following specification. The invention is clearly defined and pointed out in the claims.

A structure which is a preferred embodiment of my invention is clearly illustrated in the accompanying drawing, forming a part of this specification, in which:

Figure I is a plan view of a structure embodying the features of my invention, the circuit wires shown in connection therewith being illustrated conventionally.

Fig. II is a detail longitudinal section on a line corresponding to the broken line 2—2 of Fig. I.

Fig. III is a transverse section on a line corresponding to line 3—3 of Figs. I and II.

Fig. IV is a detail longitudinal section similar to that of Fig. II showing the connector open to receive the conductors.

Fig. V is a detail section on a line corresponding to line 5—5 of Fig. II showing details of one of the clamping members.

Fig. VI is a detail plan view of a slightly modified form of my invention.

In the drawing similar reference characters refer to similar parts throughout the several views, and the sectional views are taken looking in the direction of the little arrows at the ends of the section lines.

Referring to the drawing, the base plate 1 is preferably a stamping and has upturned flanges 2 on its longitudinal edges.

On this base flange I arrange a connector plate 3 of brass or other suitable conducting

material. The ends of this conductor plate are turned inwardly providing clamping members 4 supported in a spaced relation to the conductor plate to receive the wires 5 to be connected.

The binding screws 6 are threaded into the base plate, the screws being disposed through the clamping members 4 and the conductor plate. The screws are upset or burred at 7 to prevent their accidental removal and loss.

The inner edges of the clamping members are preferably flanged at 8 about the heads of the screws so as to guard against the wire or a strand thereof being engaged between the head of the screw and the clamping plate.

The wires 5 are shown conventionally in the drawing. It will be understood that they are frequently formed of a plurality of fine strands and these guard flanges 8 prevent such strands being engaged above the clamping members. The conductor plate and also the clamping members are preferably transversely corrugated or serrated as shown in the drawing, which adds to the gripping or holding capacity thereof.

In the preferred embodiment of my invention the arm portions 9 of the clamping members are offset oppositely as shown in Fig. I to accommodate the insulating material of the wires 5. This also aids the workmen in placing the wires so that the pull thereon tends to tighten the binding screws rather than to loosen the same.

In the embodiment shown in Fig. VI the arm portions 10 of the clamping members are centrally disposed instead of being offset as in Fig. I and the guard flanges 8 are omitted.

While the structure shown in Fig. VI is very satisfactory, the preferred embodiment illustrated has certain advantages in addition to those possessed by the structure of Fig. VI.

My improved connector is simple and economical to produce, is compact and at the same time very strong. It is easily applied or removed as occasion requires.

I have not attempted to illustrate or describe certain other modifications or adaptations which I contemplate as I believe the disclosure made will enable those skilled in the art to which my invention relates to embody or adapt the same as may be desired.

Having thus described my invention,

what I claim as new and desire to secure by Letters Patent, is:

1. In a connector, the combination of a base, a conductor plate disposed on said base and having its ends turned inwardly providing clamping members, and binding screws disposed through said clamping members and connector plate and threaded into said base plate, the bights of the inwardly turned clamping members facing inwardly permitting the engagement of a loop over the binding screws. 55
2. In a connector, the combination of a base, a conductor plate disposed on said base and having loops at its ends providing clamping members, and binding screws disposed through said clamping members and connector plate and base, the loops being disposed to face inwardly, thereby permitting 60 the engagement of loops of wire over the binding screws. 65
3. In a connector, the combination of a base having upturned flanges at its longitudinal edges, a transversely corrugated conductor plate disposed on said base between said flanges and provided with inturned transversely corrugated clamping members at its ends, and binding screws disposed 70 through said clamping members and base plate. 75
4. In a connector, the combination of a base having upturned flanges at its longitudinal edges, a conductor plate disposed on said base between said flanges and provided with inturned clamping members at its ends, the arms connecting the clamping members to the plate being oppositely offset, and binding screws disposed through 80 said clamping members and connector plate and threaded into said base plate, the inner edges of said clamping members being flanged up about the heads of the screws. 85
5. In a connector, the combination of a base having upturned flanges at its longitudinal edges, a conductor plate disposed on said base between said flanges and provided with inturned clamping members at its ends, the arms connecting the clamping members to the plate being oppositely offset, and binding screws disposed through 90 said clamping members and connector plate and threaded into said base plate, the bights of the inturned ends being reduced in width. 95
6. In a connector, the combination of a base having upturned flanges at its longitudinal edges, a conductor plate disposed on said base between said flanges and provided with inturned clamping members at its ends, and binding screws disposed through said clamping members and connector plate and threaded into said base plate, the inner edges of said clamping members being flanged up about the heads of the screws. 100

base having upturned flanges at its longitudinal edges, a conductor plate disposed on said base between said flanges and provided with inturned clamping members at its ends, and binding screws disposed through said clamping members and connector plate and threaded into said base plate, the inner edges of said clamping members being flanged up about the heads of the screws. 105

7. In a connector, the combination of a base having upturned flanges at its longitudinal edges, a conductor plate disposed on said base between said flanges and provided with inturned clamping members at its ends, and binding screws disposed through said clamping members and connector plate and threaded into said base plate. 110

8. In a connector, the combination of a base, a conductor plate disposed on said base and provided with inturned clamping members at its ends, and binding screws disposed through said clamping members, the inner edges of said clamping members being flanged up about the heads of the screws. 115

9. In a connector, the combination of a base, a conductor plate disposed on said base and provided with inturned clamping members at its ends, the arms connecting the clamping members to the plate being oppositely offset, and binding screws disposed through 120 said clamping members. 125

10. In a connector, the combination of a base, a conductor plate disposed on said base and having its ends turned inwardly providing clamping members, and binding screws disposed through said clamping members and connector and threaded into 130 said base plate, the bights of the inturned ends being reduced in width. 135

11. In a connector, the combination of a base, a conductor plate disposed on said base and having its ends turned inwardly providing clamping members, and binding screws disposed through said clamping members and connector and threaded into 140 said base plate. 145

In witness whereof, I have hereunto set my hand and seal in the presence of two witnesses.

CHARLES W. FINLEY. [L.S.]
